UNITED STATES PATENT OFFICE.

FRANK P. CAWLEY, OF PITTSBURGH, PENNSYLVANIA.

GAME APPARATUS.

1,405,967.

Specification of Letters Patent. Patented Feb. 7, 1922.

Application filed January 28, 1920. Serial No. 354,542.

To all whom it may concern:

Be it known that I, FRANK P. CAWLEY, a citizen of the United States, residing at Pittsburgh, in the county of Allegheny and 5 State of Pennsylvania, have invented certain new and useful Improvements in Game Apparatus, of which the following is a specification.

This invention relates broadly to game 10 apparatus and more particularly to a miniature bowling alley, and the primary object thereof is to provide a device of the character described, in a manner as hereinafter set forth, which is especially adapted for 15 use in the home and which requires the usual skill for playing the same as when playing the game on a bowling alley of the ordinary size.

Further objects of the invention are to 20 provide a game apparatus of the class specified which is simple in its construction and arrangement, strong, durable and efficient in its use, amusing, and comparatively inexpensive to manufacture.

To the accomplishment of these and such other objects as may hereinafter appear the invention consists of the novel construction, combination and arrangement of parts herein specifically described and illustrated in 30 the accompanying drawing, wherein is shown an embodiment of the invention, but it is to be understood that the device shown is merely illustrative and that various changes in the form, proportion and minor 35 details of construction may be resorted to, without departing from the principle or sacrificing any of the advantages of the invention, which come within the scope of the claim hereunto appended.

40 In the drawing forming a portion of this specification and wherein like numerals of reference designate corresponding parts throughout the several views:

Figure 1 is a side elevation of the bowling 45 game apparatus in accordance with this invention.

Figure 2 is a top plan view thereof.

Figure 3 is a fragmentary view of the frame and associated flexible adjusting members.

Referring in detail to the drawing the game apparatus in accordance with this invention comprises an elongated flat bowling board 1, having an upwardly curved rear 55 end 2 and secured to the lower face of the board 1, at the forward end thereof, is a rec-

tangular receptacle, having an open top and which constitutes a pin-receiver 3.

The bowling board 1 is mounted on a suitable supporting frame 4 consisting of a pair of foldable frame members 5 and 6, pivotally connected together at their centers by a horizontal bar 7. The bowling board 1 is vertically adjustable, to suit the player, upon the supporting frame 4 by expanding or contracting the frame members 5 and 6 relatively to each other by means of the flexible adjusting member 8 which is connected to the horizontal bracing rods 9 and 10, respectively securing the frame members 5 and 6.

As the bowling board 1 must be mounted on the supporting frame 4 at a perfect level, the upper ends of each of the frame members 5 and 6 are connected together with the flexible members 11 and 12 respectively, which carry the bowling board 1 and permit its ready adjustment to the level position, by slackening or drawing taut the flexible members 11 and 12, and securing the latter by means of a cleat 13, as shown in Figure 3, of the drawing.

A receiver 3, surrounding three sides of the forward end of the bowling board 1, is secured to the forward end of the latter and 85 is adapted for the reception of the projectiles 15 and the dislodged pins 16 during the playing operation. The receiver 3 consists of the bottom 17 provided with side walls 18 and 19 and with end walls 20 and 90 21, and may be detachably connected to the bowling board 1, if desired, or permanently affixed thereto.

An elongated narrow rectangular channel shaped member is arranged at one side 95 of the board 1 and provides a runway 22, and the latter is detachably carried by and spaced from the board 1. The runway 22 extends from a point in close proximity to the receiver 3 to the rear end of the apparatus and is slightly declined toward said rear end, to permit an attendant to return the projectiles 15 by gravity to the player at the rear end. The runway 22 is independent of and does not open into the receiver 3, and is in a plane to one side of the receiver 3.

The bowling board is curved at its rear end, as at 2, to give sufficient impetus to the projectile 15 to travel the length of the bowling board 1 and dislodge the pins 16 which come in contact therewith.

Bowling on a miniature board, in accordance with this invention, requires the same skill as that required on a regulation alley, and depends upon the manipulation of the 5 projectile 15 on leaving the hand of the player.

The device, being primarily intended for use in the home, may be readily set up for use or taken down and folded up so as to 10 require but little space in storing, and provides a fascinating pastime for bowling enthusiasts.

What I claim is:

A game apparatus comprising a foldable 15 frame having adjustable flexible supporting

members, a bowling board mounted on said frame and having a flat forward end and an upwardly curved rear end, a rectangular receptacle constituting a pin receiver secured to the lower face of flat forward end 20 of said board and projecting forwardly from and of greater width than said flat forward end, a runway carried by and extended from the receiver towards the curved end, and pins adapted to be mounted on the flat end 25 and adapted to be dislodged by a projectile bowled on said board.

In testimony whereof I affix my signature.

FRANK P. CAWLEY.
